UNITED STATES PATENT OFFICE.

HENRY B. COOLEY, OF KENSINGTON, CONNECTICUT, ASSIGNOR TO THE AMERICAN PAPER GOODS COMPANY, OF MONTCLAIR, NEW JERSEY, A CORPORATION OF NEW JERSEY.

MACHINE FOR PARAFFINING PAPER CUPS.

1,334,017.

Specification of Letters Patent. Patented Mar. 16, 1920.

Application filed August 18, 1916. Serial No. 115,667.

To all whom it may concern:

Be it known that I, HENRY B. COOLEY, a citizen of the United States, and a resident of Kensington, in the county of Hartford and State of Connecticut, have invented a new and Improved Machine for Paraffining Paper Cups, of which the following is a specification.

My invention relates to the class of machines used for coating articles, and especially receptacles formed from paper or the like, with paraffin, and an object of my invention, among others, is to provide a machine of this class by means of which articles may be coated with paraffin in an efficient and expeditious manner.

One form of device embodying my invention and in the construction and use of which the objects herein set out, as well as others, may be attained, is illustrated in the accompanying drawings, in which—

Figure 1 is a view in elevation of a paraffining machine embodying my invention, parts in rear of the front line of the machine being omitted.

Fig. 2 is a view in elevation of said machine looking from a point located at right angles to the point of view of Fig. 1.

Fig. 3 is a plan view of the paraffining casing.

Fig. 4 is a view in section through the casing on plane denoted by dotted line 4—4 of Fig. 3, one cup support and cup being shown in full view.

Fig. 5 is a detail view in section through said casing on plane denoted by dotted line 5—5 of Fig. 3, parts beyond being omitted.

Fig. 6 is a detail view in section through said casing on plane denoted by dotted line 6—6 of Fig. 3, the air intake tube being cut in section on a plane farther away from the observer than the general plane of section, and the scale being enlarged.

Fig. 7 is a detail view, scale enlarged, in section through a part of the casing on plane denoted by dotted line 7—7 of Fig. 3, and illustrating the construction of the air valve.

Fig. 8 is a detail view, scale enlarged, in section through the wax reservoir.

Fig. 9 is a detail view illustrating the construction and operation of the connection for the piston rod of the pump.

Fig. 10 is a plan view of the paraffining casing with the shaft supporting arm re-

moved, some of the parts being broken away 55 and others being shown in section.

Fig. 11 is a detail view, scale enlarged, illustrating the construction of the spinners and supports therefor.

Fig. 12 is a detail view illustrating the 60 construction of the presser disk mechanism.

The paraffining machine is shown and described herein in connection with a machine for forming paper receptacles, as cups, a portion of said cup forming machine only 65 being shown, and in the drawings the numeral 10 indicates a portion of the frame of such cup forming machine upon which a turret 11 is rotatably mounted, having radial arms supporting forms or molds 12 70 upon which final operations in the making of cups are performed. As this machine forms no part of the present invention details of its construction and operation are omitted herein, the showing thereof being 75 merely diagrammatic and illustrative as a means for supplying cups to my improved paraffining mechanism, it being noted that a shaft 13 on said machine constitutes a driving shaft for the paraffining machine forming the subject matter of this application, which shaft 13 is driven in the regular operation of the cup forming machine and which is for convenience merely made use of 80

as the driving shaft for the machine, shown 85 and described herein. Said cup forming machine is illustrated and described in my copending application of Serial Number 862,003, filed September 16, 1914, and reference is hereby made to said application for 90 such an understanding of the construction and operation of said machine as may be desired, although it is believed that such will not be required for a complete understanding of the invention forming the subject 95 matter hereof, it being remarked that the machine of said application comprises a support for a roll of a strip of paper 14 from which the cup bottoms are formed.

Standards 15 of any suitable form and construction joined by bars 16 comprise a frame within which sprocket wheel shafts 17—18—19 are supported, there being a pair of wheels located on each of said shafts adapted to receive a carrier 20 in the form 105 of sprocket chains that are connected by supporting shells 21 formed to receive the cups or receptacles to be operated upon,

These shells have ears 22 secured to the chains in any suitable manner, each shell with its ears being secured at opposite sides to a length of said chains. These chains 5 may be supported on idler gears 136.

The shaft 18 is intermittently driven as by means of intermeshing beveled pinions (shown in dotted lines in Fig. 1) one of which pinions is secured to a shaft 23 10 mounted in brackets 24 secured to the frame and having a ratchet wheel 25 engaged by a pawl 26 on one branch of a forked arm 27, mounted to rock on said shaft and connected by a rod 28 with the shaft 13, said rod being 15 forked to straddle the shaft 13 and engaging a carrier driving cam 29 secured thereto and by means of which parts the carrier chain is given a one step movement at each rotation of the shaft 13, when said shaft, as 20 in the present case, makes a complete rotation each time the formation of a cup on the turret 11 is completed.

The cups 30 are forced from the molds 12 by any suitable means and in a manner to 25 fall into a chute 31 having a flaring mouth to receive the cups and so located that a shell 21, at each time the carrier chain stops in its step-by-step progressive movement, is located under the delivery end of said chute 30 so that the cups are delivered to and fall into each of the shells as they pass underneath the chute and as shown in Fig. 1 of the drawings.

A presser disk 32 is loosely attached to a 35 presser bar 33 pivotally mounted on the frame and connected by a presser rod 34 with a lever 35 pivotally mounted in a bracket 36 supported on the frame 10 and connected at one end with a rod 37 operationally engaged with a presser operating cam 38 secured to the shaft 13. A shell 21 is 40 located underneath the presser each time the carrier chain halts in its step-by-step movement and by the mechanism above described 45 the presser is forced into contact with each cup after it has been deposited in the shell, thus pressing the cup in firm engagement with the walls of the shell so that it will not be accidentally removed therefrom.

The shaft 19 is mounted in bearing blocks 43 that may be adjusted as by means of screws 44 to regulate the tension of the carrier. A supporting plate 45 is mounted on the frame in position to receive and support 55 the cups as they travel the upward reach of the chain as shown in Fig. 1 of the drawings. The cups pass off the end of this plate and over a paraffining casing within which they are coated with paraffin. This casing 60 consists of a base 46 and a receiving shell 47 of cylindrical form secured to and supported on the base. The base 46 includes a pan 48 smaller in diameter than the base and having a flange 49 by means of which it is 65 secured to the upper edge of the base, there-

by forming a heating chamber 50 between the outer surface of the pan and the inner surface of the base. A steam pipe 51 extends into this chamber to supply steam thereto for the purpose of heating the contents, as wax, of the pan which heated contents pass out through a drainage pipe 52. A spinner carrier is rotatably mounted on a supporting post 53 rising from the bottom of the pan 48, this carrier comprising a 70 base plate 54 and a spinner supporting plate 55 having depending flanges forming a gear chamber, which chamber is closed by the base plate 54. A bearing and driving sleeve 56 extends from the plate 55 of the carrier 75 and a spinner connecting shaft 57 is rotatably mounted in this sleeve and has a beveled gear 58 secured at one end meshing with a beveled gear 59 on a spinner driving shaft bearing driving pulleys 60 that may 80 receive a belt from any suitable source of power. A gear 61 secured to the lower end of the connecting shaft 57 meshes with pinions 62 secured to the ends of spinner shafts 63 rotatably mounted in spinner supporting 85 sleeves 64 rising from the carrier and with their lower ends projecting into hubs in the gear chamber in the carrier, as shown in Fig. 4 of the drawings. Any suitable number 90 (six in the construction herein shown) of these spinner shafts are provided, each shaft extending into a spinner chamber 84 formed by webs 85 radially arranged and extending upwardly from the plate 55, as 95 shown in Fig. 10 of the drawings, and spinners 65 are secured to the upper ends of the shafts and are of a form to receive receptacles or cups 30 on their outer surfaces. A sprocket wheel 66 is secured to the sleeve 56 and receives a carrier driving chain 67 extending to a sprocket wheel on a carrier driving shaft 68 mounted in bearings in brackets 69—70 secured to the paraffining casing. An arch 71 is secured to and extends across the upper edge of the receiving 100 shell and contains the bearings for the upper end of the connecting shaft 57. A bracket 72 depends from the under side of said arch and contains a brake 73 that surrounds the sleeve 56, a bushing 74 of any 105 suitable material located within the brake being held in frictional contact with the sleeve as by means of a clamp screw 75.

Each of the sleeves 64 has an extension 76 with a mouth 77 from which an air passage 78 leads through said extension and sleeve and opens within the spinners 65 that have ejecting slots 79 in their upper ends. As the carrier is given a step-by-step rotation by means of its driving connection with the 110 shaft 23 that has an intermittent movement as hereinbefore described, a mouth 77 is located, each time the carrier stops, underneath an air delivery opening 80 from a chamber 81 in a hub 82 rising from a plate 115 120 125 130

83 secured to the upper edge of the shell 47 of the paraffining casing and projecting over the edge of said shell. A valve case 86 is mounted for reciprocating movement in the 5 arms 87 of a bracket 88 secured to a peripheral flange extending about the upper edge of the shell 47. The valve case has a valve chamber 89 closed by a cap 90 secured to the case and receiving an air supply pipe 10 91 that extends to any suitable source for air under pressure. A valve 92 within the chamber 89 has a valve actuating rod 93 extending downwardly through a nipple 94 that has its lower end extending into the 15 chamber 81. An actuating disk 95 on the lower end of the rod 93 is adapted to engage a shoulder in the chamber 81 at a point where it communicates with the air delivery opening 80. A valve actuating lever 96 has 20 forked arms with supporting pins extending into a groove 97 in the valve case 86, this lever being supported on a bracket 98 secured to and rising from the upper edge of the shell 47, as shown in Fig. 6 of the 25 drawings. A valve operating bar 99 is pivotally attached to the lever 96 at one end and to a valve operating arm 100 at the opposite end, said arm being pivotally supported at one end on any suitable part of 30 the machine, and having a roller 101 resting in contact with a valve operating cam 102 secured to the shaft 13.

This cam is shaped and the parts are mounted and timed in their operation to 35 move the valve case downwardly at each time a mouth 77 is presented underneath the air delivery opening 80. In such movement of the case the disk 95 strikes the shoulder in the bottom of the chamber 81, lifting the 40 valve 92 from its seat and permitting air to flow into the extension 76, which action creates a blast of air from the passage 78 and within the spinner 65 thereby blowing the cup 30 from the spinner. In this upward movement of the cups from the spinner, they are guided by fingers 103 extending in a curved path to cause the cups to 45 fall into a trough 104 by which they are delivered to any suitable point.

50 It will be noted that the spinners 65 and the cups thereon are rapidly rotated by the mechanism hereinbefore described and that while thus rapidly rotating the carrier containing the chambers 84 within which the 55 spinners are mounted is also rotated to revolve the spinners and the cups about the axis of the carrier to bring the spinners successively in position for the different operations.

60 As the cups are successively located by the carrier 20 over the shell 47, and at the time the carrier stops its movement with a cup in this position, a pusher 105 is pressed upon the bottom of the cup to force it from a supporting shell 21. The spinner carrier being

connected up to receive the intermittent movement imparted to the carrier chain, makes each stop in its step by step movement with a spinner directly underneath a supporting shell, so that the cups as they 70 are forced from the shell drop on to the spinners and immediately take up the rotative movement thereof. The pusher 105 is located at the end of a downwardly projecting bar from a pusher lever 106 pivotally 75 mounted on a pusher support 107 secured to and rising from the frame. The lever 106 is actuated by a pusher rod 108 extending downwardly and having a forked end straddling the driving shaft 13 and with a roller 80 in engagement with a pusher operating cam 109 secured to said shaft, the movements of the pusher being so timed that one or more downward movements will take place during the dwell of each of the supporting shells 85 therein.

After each receptacle has been deposited upon a spinner, the spinner carrier is given a one step movement to locate the spinner in due course underneath a spraying nozzle 90 110, the carrier rotating in the direction indicated by the arrow shown in Fig. 3. A spraying chamber plate 111 of substantially the cross-sectional shape of the chambers 84 is secured to the upper edge of the shell 95 47, projecting inwardly therefrom in position to form a cover for one of said chambers each time the spinner carrier halts in its rotary movement. A plate 112 of substantially the same shape overlies and covers 100 said chambers at the location of the air supply. The nozzle 110 is connected by pipes 113-114 with a delivery pipe 115 extending from a pump 116 of any ordinary construction and which has a pressure chamber 117, 105 the pipe 115 having a blow-off 118. Said pump is located in a wax supply tank 119 surrounded by a heating chamber 120 within a jacket 137 and into which steam is introduced through a steam pipe 121 connected 110 with a main steam supply pipe 122 extending from any suitable source of steam supply. The drain pipe 52 from the pan 48 empties into the tank 119 through a trough 138, all the surplus wax that flows off from 115 the cups in the waxing process, dropping on to the plate 55, and, passing through strainers 123 covering notches 124 in the edge of the disk, and in each spinner chamber therein, flows back to the wax supply tank 119. 120

The pusher 105 is located immediately over the receiving station and as the spinner carrier halts with a chamber 84 at this point, such chamber becomes a receiving chamber. The spraying nozzle 110 is located at the 125 spraying station, and as each chamber, in the step-by-step movement of the spinner carrier halts at this point, it becomes a spraying chamber. In the next location of each chamber after passing the spraying sta- 130

tion, the spinners continue to rotate the cups to clear therefrom any surplus wax that may be contained therein, and this takes place at the clearing station, and each chamber at 5 this point becomes a clearing chamber. The next position of the chambers as the carrier halts in its step-by-step movement is at the ejection station, and as each chamber 84 comes to rest at this point and underneath 10 the plate 112, such chambers become ejection chambers.

The rate of rotation of the spinners and therefore of the cups thereon, is so regulated that all of the surplus wax will be thrown 15 from the cups by centrifugal force, and the provision of a clearing station or clearing chamber enables this operation to be well done. As a further means for regulating the amount of paraffin that will be deposited 20 upon the cups, a regulating pipe 139 is provided extending from the delivery pipe 115 into the tank 119, said pipe having a valve 140 for regulating the flow through said pipe. If this valve be open to any extent, a 25 part of the paraffin taken up by the pump will be passed back to the tank, and the amount of flow passing through the spraying nozzle 110 onto the cups may be thus nicely regulated.

30 The pump is operated from the shaft 13 by means of a gear 125 thereon, meshing with a gear 126 on a pump actuating shaft 127 mounted in suitable bearings in the frame and having secured thereto a crank 35 disk 128 with a slot 129 extending thereacross to receive a crank block 130 having a crank pin 131 projecting therefrom. The block 130 is adjustable along the slot 129 and is secured as by means of screws passing through slots in the disk, block, or both, 40 as shown in Figs. 8 and 9, this to regulate the amount of movement of the pump plunger. The pin 131 engages a yielding block 132 held between springs 133 in a pump rod 45 bar 134 secured to an end of a pump rod 135 the other end of which rod is connected to the plunger of the pump. This connection will permit a forced stopping of the movements of the pump plunger without injury 50 to the parts, the rotation of the crank disk being permitted under such conditions.

The cups being delivered to the carrier 20 through the chute 31 are carried along in the direction indicated by the arrow in Fig. 55 1, and some time thus elapses between the delivery of the cups to the carrier and the paraffining operation, so that the adhesive used in making the cups has a chance to dry before the cups are subjected to the paraffining operation.

The further operation of the machine will be readily understood it being briefly stated that the operation of the air valve is timed to correspond with the step-by-step movements of the spinner carrier so that the air

blast takes place at each time said carrier stops its rotating movement.

In accordance with the provisions of the patent statutes, I have described the principle of operation of my invention, together 70 with the apparatus which I now consider to represent the best embodiment thereof; but I desire to have it understood that the apparatus shown is only illustrative, and that the invention can be carried out by other 75 means.

I claim—

1. In a cup paraffining machine, a carrier to convey cups, a spraying mechanism located to receive cups from the carrier and comprising a movably mounted member having compartments, and means for moving the spraying member and carrier in unison whereby the cups may be delivered to different compartments in the spraying device. 80

2. In a cup paraffining machine, a carrier to receive cups in a plurality of defined positions thereon and to convey said cups, a spraying mechanism located to receive cups from a carrier and comprising a mov- 90 ably mounted member having means to receive cups in defined positions thereon, and means for causing movement in unison of said carrier and spraying member to deliver cups at said defined position on the 95 spraying device.

3. In a cup paraffining machine, a carrier to convey cups and a spraying mechanism located to receive cups from the carrier and comprising a support, means for producing a step by step movement relatively as between said carrier and support, said spraying device having compartments to receive cups, and means for halting one of said members to permit delivery of cups 100 to the successive compartments in the spray- 105 ing device.

4. In a cup paraffining machine, two members including a carrier to receive cups in a plurality of positions thereon to 110 convey said cups and a support comprising a part of a spraying device, both having step by step movements, and said support having means to receive cups in defined positions thereon, and means for simultaneously halting said members to permit 115 proper delivery of the cups to the spraying device.

5. In a cup paraffining machine, a carrier to receive cups in a plurality of positions thereon to convey said cups and a spraying mechanism comprising a movably mounted member located to receive cups from the carrier and both having step by step movements, defined means on both of said devices 125 for receiving cups, and means for simultaneously halting both of said devices to permit the delivery of cups in the defined positions on the spraying device.

6. A receiving shell, a spinner carrier 130

- movable within the shell, a spinner rotatably mounted on the carrier, means for rotating the spinner independently of the movement of said carrier, and a spraying device for spraying cups upon the spinner.
7. A receiving shell, a spinner carrier rotatably mounted within the shell, a spinner rotatably mounted on the carrier, means for operating the carrier, means for rotating the spinner independently of the movement of said carrier, and a spraying device for spraying cups upon the spinner.
- 10 8. A receiving shell, a spinner carrier rotatably mounted within the shell and including radially arranged walls forming chambers, spinners located within said chambers, means for rotating the carrier, means for rotating the spinners, and means for spraying cups upon the spinners.
- 15 9. A receiving shell, a spinner carrier movable within the shell and including a chamber, a cover upon the shell to close the upper end of said chamber, means for operating upon a cup within said chamber, means for moving said carrier, a spinner located on the carrier, and means for rotating the spinner independently of the movement of said carrier.
- 20 10. A receiving shell, a spinner carrier rotatably mounted within the shell and including radially arranged walls forming chambers, a cover on the shell to close the upper ends of said chambers, spinners rotatably mounted within the chambers, means for rotating the spinners, means for operating upon cups within said chambers, and means for rotating the carrier.
- 25 11. A receiving shell, a spinner carrier rotatably mounted within the shell and including radially arranged walls forming chambers, means for imparting a step by step rotation to said carrier, a plate positioned to overlie and cover each chamber as it comes to rest underneath said plate in the step by step movement of the carrier, spinners rotatably mounted in said chambers, means for rotating the spinners, and means for operating upon cups within said chambers when covered.
- 30 12. A receiving shell, a spinner carrier movable within the shell and including a chamber, a cover upon the shell to close the upper end of said chamber when located underneath the cover, means for moving the carrier, a spinner mounted on the carrier, means for rotating the spinner independently of the movement of said carrier, and means for spraying cups within said closed chamber.
- 35 13. A receiving shell, a spinner carrier rotatably mounted within the shell and including radially arranged walls forming chambers, means for imparting a step by step movement to said carrier, a plate positioned to overlie and cover a chamber dur-
- ing each period of rest of said carrier, spinners mounted on said carrier, means for rotating the spinners, and a spraying device extending through said plate to successively spray cups in each of said chambers as they come to rest under said plate.
- 40 14. A receiving shell, a spinner carrier movable within the shell and including a chamber, means for moving the carrier, a spinner mounted on the carrier, means for rotating the spinner independently of the movement of said carrier, a continuously operated spraying device for spraying cups within said chamber, and means for operating said spraying device.
- 45 15. A receiving shell, a spinner carrier movable within the shell and including a chamber, means for operating upon cups within said chamber, a spinner mounted upon the carrier, means for rotating the spinner, a pneumatic tube appurtenant to said spinner and movable therewith, and means for projecting air through the tube to eject cups from said spinner.
- 50 16. A receiving shell, a spinner carrier movable within the shell and including a chamber, means for operating upon cups within said chamber, a cover upon the shell to close the upper end of said chamber when located underneath the cover, a spinner located on the carrier, means for imparting intermittent movement to said carrier, a pneumatic tube opening appurtenant to said spinner, and means for intermittently operating said pneumatic device to eject cups from said spinner.
- 55 17. A receiving shell, a spinner carrier rotatably mounted within the shell and including radially arranged walls forming spinner chambers, spinners mounted in said chambers, means for rotating the spinners, means for intermittently rotating the carrier, plates positioned to cover a plural number of said chambers at each period of rest of the carrier, means for spraying cups in each of said chambers when closed by one of said plates, a pneumatic tube opening appurtenant to another of said plates, and means for projecting air from said tube to eject cups from the spinners when located underneath the other of said plates.
- 60 18. A receiving shell, a spinner carrier rotatably mounted within the shell and comprising a sleeve, means for operating upon cups within said shell, means for rotating the sleeve, a shaft extending through the sleeve, means for rotating the shaft, spinners supported by the carrier, and connections between said shaft and spinners for rotating the latter.
- 65 19. A receiving shell including a heating chamber at the bottom thereof, a carrier rotatably mounted within the shell above said chamber, means for rotating the carrier, spinners mounted on the carrier, means for

rotating the spinners, independently of the movement of the carrier, and means for spraying cups when located on said spinners.

20. A receiving shell including a heating chamber at the bottom thereof, and a paraffining chamber at its upper part, passages for flow of liquid between said chambers, a carrier mounted in the upper chamber, means for operating the carrier, spinners located on the carrier, means for rotating the spinners independently of the movement of the carrier, and means for spraying cups when located on said spinners.

21. A receiving shell, a spinner carrier mounted within the shell, means for operating the carrier, spinners located on the carrier, means for rotating the spinners independently of the movement of the carrier, a spraying device, a pump, and a connection between the spraying device and pump for supplying liquid to be sprayed on cups on the spinners.

22. A receiving shell, including a chamber at the bottom thereof and a spinner chamber, a carrier and means for rotating it, spinners located in said spinner chamber, means for rotating the spinners independently of the movement of the carrier, a spraying device, a pump, a connection between the spraying device and pump, and a connection for flow of fluid from the chamber at the bottom of the shell to the pump.

23. A receiving shell including a heating chamber at the bottom thereof and a spinner chamber, a carrier and means for rotating it, spinners located in said spinner chamber, means for rotating the spinners independently of the movement of the carrier, a spraying device, a pump, a connection between said spraying device and pump, and a connection for flow of fluid from said heating chamber to said pump.

24. A receiving shell having a heating chamber and a paraffining chamber, a carrier with means for rotating it, spinners located on the carrier, means for rotating the spinners independently of the movement of the carrier, a spraying device for spraying cups on said spinners, a pump connected with the spraying device and including a plunger and a pump actuator, a yielding connection between said plunger and actuator, and a connection between said heating chamber and pump for flow of liquid from one to the other.

25. In a cup paraffining machine, a carrier to convey cups, means to deliver cups to said carrier, means for moving said carrier and delivery means in unison whereby the cups may be delivered to different locations on the carrier, means to receive cups from said carrier, and means for coating said cups, while located on said receiving means.

26. In a cup paraffining machine comprising two members including a carrier to con-

vey cups, means to deliver cups to said carrier, means for moving said members with a step-by-step movement, means for moving said members in unison to permit delivery of cups from one to the other, means to receive cups from said carrier, and means for coating said cups, while located on said receiving means.

27. In a cup treating machine, a carrier chain, means for intermittently operating said chain, a spinner carrier located to receive cups from the carrier chain, means for intermittently rotating said carrier in unison with said chain, and means for operating upon cups upon said carrier.

28. In a cup treating machine, a carrier chain, means for imparting intermittent movement to said chain, a receiving shell, a spinner carrier located within the shell to receive cups from the carrier chain, means for intermittently rotating said carrier in unison with said chain, spinners located on the carrier, means for rotating the spinners, and means for operating upon a cup upon said carrier.

29. In a cup treating machine, a receiving shell, a spinner carrier rotatably mounted within the shell, spinners located upon the carrier, means for rotating the spinner independently of the movement of the carrier, means for projecting a coating material onto the cups on the spinners, and means for regulating the amount of coating material that will be retained on the cups.

30. In a cup treating machine, a receiving shell, a spinner carrier rotatably mounted within the shell, spinners mounted upon the carrier, means for rotating the spinner independently of the movement of the carrier, means for delivering a coating material onto the cups, and means for regulating the amount of material passing through the spraying means.

31. In a cup treating machine, a receiving shell, a spinner carrier intermittently rotatably mounted within the shell, means for imparting a step-by-step movement to the carrier, spinners located upon the carrier, means for delivering a coating material upon the cups, and means for ejecting the cups, said ejection means being located at such distance from the coating means as to permit each cup to remain on a spinner during one of the stopping movements of the carrier while passing from the coating to ejecting position.

32. In a cup treating machine, a receiving shell, a spinner carrier rotatably mounted within the shell and including radially arranged walls forming chambers comprising a receiving station, a spraying station, a clearing station, and an ejection station, means for causing a step-by-step movement of the carrier and a halt in such movement with a chamber at each of said stations, and

means for operating upon a cup at one of said stations.

33. In a cup treating machine, an endless carrier chain comprising shells of tapered form with their larger ends opening inwardly, means for delivering cups into the wider ends of the shell on the lower reach of the chain, means for pressing the cups out of the shell while traveling along the upper 5 reach of the chain, means to receive cups from said chain, and means to perform a coating operation upon said cups.
34. A receiving shell, a spinner carrier movably mounted within the shell, a spinner 10 rotatably mounted on the carrier, means for operating the carrier, a chamber located within the carrier, a cover for said carrier, means for coating cups on said carrier, and means for introducing blasts of air into said 15 chamber to remove cups therefrom.
- 20

35. In a cup paraffining machine, a carrier having a step-by-step movement, means having a step-by-step movement for delivering cups to said carrier, a spraying device having compartments to receive cups, means for imparting a step-by-step movement to said spraying device in unison with said carrier and said delivering means, and means for spraying cups on said spraying device. 25

36. In a cup paraffining machine, a carrier having a step-by-step movement, means for delivering cups to the carrier, means for imparting a step-by-step movement to said delivering means, a spraying device having compartments to receive cups, means for imparting step-by-step movement to said spraying device, and means for spraying cups 30 35 thereon.
